UNITED STATES PATENT OFFICE.

EMMIT G. LATTA, OF SYRACUSE, NEW YORK, ASSIGNOR TO CORONA TYPEWRITER COMPANY, INC., A CORPORATION OF NEW YORK.

TYPE-WRITING MACHINE.

1,278,947.

Specification of Letters Patent. Patented Sept. 17, 1918

Application filed July 1, 1916. Serial No. 107,133.

To all whom it may concern:

Be it known that I, EMMIT G. LATTA, a citizen of the United States, and a resident of Syracuse, county of Onondaga, and State

5 of New York, have invented certain new and useful Improvements in Type-Writing Machines, of which the following is a full, clear, and exact description.

This invention relates more particularly 10 to a small, portable, visible writing machine adapted to be made more compact when not in use than when in a normal operative condition.

One of the principal objects of the invention is to provide a small, compact typewriting machine which may be collapsed to occupy but little space when not in use, and to embody in such machine a platen shift mechanism particularly adapted for machines of 15 this character, and so to construct the parts that no special attention is required because of interference or disconnection of the parts when it is desired to collapse the machine to make the same occupy less space for transportation or other purposes.

Another object of the invention is to provide a typewriting machine having its main frame comprising a plurality of parts relatively movable with respect to each other 20 and having the carriage and coöperating mechanism mounted on one part of the main frame and the type action on another part.

Other objects of the invention are to provide a typewriter in which one frame part is 25 hinged to another frame part to have an up and down movement relatively thereto, and each part adapted to support parts of the typewriter mechanism; to provide a standard keyboard having a part thereof mounted 30 upon the movable part of the frame; to provide simple and efficient platen shift mechanism for the carriage to adapt the type-bars to have a plurality of characters thereon; and to provide a writing machine 35 in which the universal bar is mounted upon a movable part of the main frame independent of the case shift movement.

A further object of the invention is to provide simple and efficient means whereby 40 a carriage may be mounted to travel on a hinged frame and the latter moved by shift mechanism all of which are mounted upon the movable part of the main frame and partake of its compact movement.

A still further object of the invention is 55 to provide a machine which is simple in construction and may be readily made and assembled.

With these and other objects in view, the invention will be hereinafter more particularly described with reference to the accompanying drawings, which form a part of this specification, and will then be pointed out in the claims at the end of the description.

In the drawings, Figure 1 is a side elevation of one form of machine embodying the invention, showing the parts in their normal operative position.

Fig. 2 is a side elevation similar to Fig. 1, 70 except that the parts are in a collapsed or compact position.

Fig. 3 is a fragmentary vertical section taken on the line III—III of Fig. 12.

Fig. 4 is a fragmentary section of one of 75 the ribbon spools.

Fig. 5 is a sectional elevation taken from front to rear of the machine, some of the parts being left out to avoid confusion.

Figs. 6 to 10 are detail views of parts 80 of the key-operated levers and type action.

Fig. 11 is a detail view of the platen shift levers and the part operated thereby.

Fig. 12 is a plan view, partly broken away and partly in section, with some of the 85 parts removed for the purpose of better illustrating the invention.

Fig. 13 is an elevation of the escapement mechanism.

Fig. 14 is a fragmentary vertical section 90 from front to rear of the machine, showing the action for the end type-bars.

Fig. 15 is a view similar to Fig. 14, except that it shows the means whereby the space bar may be made to operate the universal bar.

Fig. 16 is a detail elevation of the lever to which the links of the end type-bars are connected; and

Fig. 17 is a detail elevation of the lower 100 lever which coöperates with the lever shown in Fig. 16 to form a pair for each end type-bar.

The main frame 10 of the machine 105 comprises a plurality of parts. As shown, it comprises a base, member or frame part 11, and a movable member or frame part 12. The frame part 11 forming a base for the

machine is located normally partly within the movable frame part 12, and said frame part 12 is hinged at 13 on opposite sides of the machine by screws or otherwise, to adapt 5 the member 12 to have an up and down vertical movement while upright about the base member or frame part 11, and serve substantially to inclose the frame part 11 when in a compact condition. The frame part or 10 base 11 has means for the attachment of rubber or other feet 14, and has side plates 15 and 16 which are connected together by means of bars 17, 18 and 19. This inner frame part 11 may be an integral casting or 15 otherwise formed as desired, with the bars 18 and 19, as well as the bar 17, all or any one of them detachable, as preferred. The outer frame part 12 may comprise the side plates 20 and 21, and these plates may be 20 connected at the front portion by an integral transversely extending bar or part 22, and a rear bar or part 23, and said member or frame part may be of an integral casting or 25 otherwise formed with the bars 22 and 23 detachable or not, as desired. Each of the side plates 20 and 21 is provided with a curved slot 24 having a radius with the pivot 13 as a center. Extending through each of 30 said slots 24 is a thumb screw 25. This thumb screw, Fig. 3, has an annular portion 26, which is adapted to be seated in recesses located at the upper and lower portions of the slot 24, and has a stem portion 27, which is adapted to engage a threaded aperture in 35 one of the side plates of the base 11. When the frame parts are in the position shown in Fig. 1 and the thumb screw at each side of the machine tightened, the outer frame part will be held in an extended position against 40 movement, and by releasing the thumb screws 25 the outer frame part 12 may be moved on its pivots 13 to the collapsed position shown in Fig. 2. The parts may be rigidly held together in this collapsed condition by tightening the thumb screws and 45 in this condition materially reduces the height of the frame, and makes the same more convenient for packing or transportation purposes.

50 A plurality of levers 28 are pivotally held to the upper portion of the transversely extending bar 17 and a plurality of levers 29 are pivotally held at the lower portion of said bar 17. The bar 17 is slotted along its upper and lower edges to receive the levers 28 and 29, and extending lengthwise of the 55 bar at the upper portion thereof is a fulcrum rod 30 for the levers 28, and at the lower portion of said bar is a fulcrum rod 31 for the levers 29. The levers 28 and 29 are substantially horizontally arranged, and 60 are disposed in pairs, one above the other, and each pair of levers is connected by a stem 32 of one of the key-operated levers 33, 34, 65 or 35. These key-operated levers 33, 34 and 35 have the stem portion thereof similarly constructed so as to be pivotally held to the levers 28 and 29 at the rear of the bar 17. One of the levers, as the lever 34, has its stem portion substantially straight, while 70 the upper part of the lever 33 extends forwardly, and the upper part of the key-operated lever 35 extends upwardly and rearwardly. The purpose of having the levers 33 to 35 constructed as shown is to provide 75 a series of banks of keys 36 forming a part of the usual standard or universal keyboard, and so that the keys may provide a substantially uniform touch. The levers 28 have a forwardly extending portion 37 provided 80 with a series of apertures, any one of which is adapted to be engaged by a spring 38. Each spring 38 is connected at its lower end to a forwardly extending part of a plate 39, which is secured to the transversely extending bar 17, and said spring serves to return each lever 37 and its connected key-operated lever to its normal operative position after being depressed. The levers 29 are 85 substantially T-shaped in form, at least the greater number of the same, and substantially all of said levers except about four of the end levers at each side of the machine, as will be presently described. The stem 40 of each lever 29 is pivotally connected to a rearwardly extending link 41 and the rear end of said link 41 is pivoted to a lug 42 of a type-bar 43. The type-bars 43 are pivoted to a wire or rod 44, arranged in a segment 45, said segment being held to the transversely 100 extending bar 19. At the forward end of each type-bar 43 is a block or head 46, on which are a plurality of characters 47. There may be two or more characters, according to whether the machine has a single 105 or double case shift. As shown, the machine has a double case shift, and the type heads or blocks are therefore provided with three characters, one for the upper case, another for lower case, and the third for figures, etc., or otherwise, as preferred. The type-bars normally rest upon a felt or other cushion 48, extending along the bar 18, which bar, as already stated, is connected between the side plates 15 and 16 of the base or frame 115 part 11. As the keys 36 are depressed the levers 28 and 29 will be forced downwardly, and this will exert a pulling action on the type-bars and force the type upwardly and rearwardly against the work sheet about a 120 platen 49 mounted in a transversely movable carriage 50.

The outer type-bars are pivotally held and supported as already described, but these type-bars, usually four in number at each 125 side of the machine, instead of being connected to the lower levers 29, are connected to levers 50^a, Fig. 14, corresponding somewhat to the shape of the levers 29. These levers 50^a are connected to the stems of the 130

end key-operated levers, and each of said end key-operated levers is pivoted to a link or lever 50^a thereby providing pairs of levers in a manner similar to the remainder of the 5 key-operated levers. The upper levers 50^a are each provided with a projecting stem portion 50^c which is connected to one of the links of the type-bars to operate the same, and is provided with a forwardly projecting part 50^d to which a spring 50^e is connected, said springs being held to the plate 39 in a manner similar to the springs 38 and like said springs serve to return the key-operated levers to their normal position. 10 The bar 17 is cut away to provide free movement to the projecting part 50^c of the levers 50^a. The purpose of having the links of the end type-bars connected to the upper levers 50^a, while the links of the other type-bars 20 are connected to the lower levers, is that a more direct connection is thus made with the type-bars and a more uniform touch obtained.

The carriage 50 comprises end plates or 25 brackets 51, which are connected together at the forward edge by a rail 52 and at the rear portion thereof by a rail 53. These rails are grooved, and are opposed to grooves in rails 54 and 55 respectively, so as to provide 30 raceways for anti-friction devices, as balls 56, to adapt the carriage to travel readily transversely of the machine under the tension of a spring in a drum 57, which is mounted upon a shift frame 58, said 35 drum being provided with means to vary the tension of the spring and connected by a strap 59 or other flexible connection to a rearwardly extending part 60 of one of the carriage end plates 51. The rails 54 and 55 40 form a part of the shift frame, and the rail 54 is pivotally mounted by means of screws 61, Fig. 12, or otherwise to lugs 62 on the movable frame part 12 to adapt the carriage and shift frame to be moved with 45 the parts mounted thereon relatively to the types for case shift purposes, by mechanism to be presently described.

As a means to shift the frame 58 and carriage, various means may be employed. As 50 shown, the shift frame 58 is provided with a roll or a plurality of rolls 64, Figs. 5 and 11, which are held to a stud or pin 65 projecting outwardly from one of the side rails 63 of the shift frame. The rolls 64 are 55 adapted to be engaged by shift levers 66 and 67. The two shift levers 66 and 67 are both pivoted to a lug 68 projecting inwardly from the side plate 20 of the movable frame part 12, and each lever is substantially 60 bell-crank in form, having a forwardly extending part 69 on which is a key 70, and an upwardly and rearwardly extending part 71. The part 71 of the lever 66 is longer than the same part of the lever 67, and said part 71 of the lever 66 is pro-

vided with a cam slot 72 at the upper portion thereof, while the lever 67 is provided with a cam slot 73 at the upper portion thereof, and are each adapted to engage one of the rolls 64 on the shift frame, said rolls 70 being spaced by a suitable washer. The cam slots 72 extend upwardly and rearwardly, while the slot 73 extends downwardly and rearwardly, and during the operation of the shift lever 66 will raise the 75 roll and shift frame with the carriage and parts mounted thereon from the normal position shown, while on the depression of the lever 67 the cam slot will cause the shift frame to be lowered from the normal operative position shown. It will be evident that the cam slot 73 prevents the roller from passing too far down when returning from the upper case position, and the cam slot 72 of the lever 67 serves not only to shift the 80 roller and shift frame upwardly, but holds it against movement above its central position when returning from the lower shift position, said cam slots being made the exact 85 length to move the roller the proper distance when it is at the extreme end of the cam, and in this way the two cam slots guard against vibration of the roller and shift frame with the carriage in all of its three positions. The weight of the shift 90 frame and carriage is nearly balanced by a suitable spring 74, which is secured to the rear bar 23, and the shift levers are returned to their normal positions as soon as their finger keys are released by spring 74^a, said 95 shift levers being adapted to engage a back stop or rest 75, Fig. 12, against which the arms are normally held by their retracting springs. The shift levers as thus mounted have the keys forming a part of the keyboard, and by having the shift levers mounted upon the movable frame part 12, the keyboard is thus partly mounted upon a stationary part of the main frame, and a further part upon the movable part of the 100 main frame.

A universal bar frame 76 having a universal bar 77 at the forward portion thereof is pivoted to a transversely extending rod 78. The rod 78 is held between the side plates 115 20 and 21 of the movable frame part 12, and partakes of its compact movement. The universal bar 77 is adapted to be engaged by lugs or projecting portions 79 on each of the key-operated levers 33, 34 and 35, so that on 120 the depression of any one of said levers the universal bar will be moved downwardly with the rod 78 as a pivot. A link 80 is pivotally held at its lower end to each of the rearwardly extending rails of the universal 125 bar frame 76 and at the upper end each link is pivotally connected to the forwardly extending arm of a lever 81. There are two levers 81 one at each side of the machine, and each lever is pivoted at 82 to a lug or 130

projection 83. The rear arm 84 of each lever 81 extends rearwardly and downwardly and is connected by an integral rod portion 85. On the rod portion 85 is a rearwardly extending arm 86 having an angular portion 87 which is adapted to engage the end 88 of a dog carrier 89. This dog carrier 89, Fig. 13, is loosely pivoted on a pin 90, and is provided with a slot 91 to adapt the same to have a relative movement on its fulcrum pin 90. The carrier 89 is provided with dogs 92 and 93 which are adapted alternately to engage the teeth 94 of an escapement wheel 95, said dog carrier being normally forced in one direction by a spring 96. On the stud or pin 96^a, and formed separately or integral with the wheel 95 is a pinion 97, which is adapted to engage a rack 98 extending lengthwise of the carriage 50 to travel therewith.

When any one of the key-operated levers is depressed the projecting portion or lug 79 thereof will engage the universal bar 77 and will depress the same, thereby moving the links 80, levers 81 and rod 85 on the pivots 82 to move the part 86 upwardly into engagement with the end 88 of the dog carrier, thus releasing the dog 93 from one of the teeth of the toothed wheel 95. As soon as the dog 93 is released the dog 92 is moved into the path of another tooth of the toothed wheel, and prevents the wheel from moving more than the space of one tooth corresponding to a letter space of the carriage, as is usual in escapements of this kind. The purpose of the spring 96 is to give the dog carrier 89 a slight movement by reason of the slot 91 to prevent the dog 93 from again engaging the same tooth of the wheel 95. This particular escapement is not specifically claimed herein, having been made a part of a separate application, Serial No. 102,934, filed June 10, 1916. The escapement mechanism, as well as the tension means, with the exception of the universal bar, is mounted upon the shift frame, and partakes of the shift movement.

A space bar 98^a, Fig. 1, 5, 12 and 15 is supported by arms 98^b. These arms 98^b are pivoted at their inner ends to brackets on the transversely extending bar 18 and one of said arms or both of them, if desired, has a pin 98^c which enters a slot in a lever 98^d. The lever 98^d is pivoted to the rod 30, on the slotted transversely extending fulcrum bar 17 and at the outer end is held by a spring 99 similar to the springs 38. The rear end of the lever 98^d is adapted to engage and operate the universal bar 77 when the space bar 98 is depressed; thus the universal bar is actuated not only by the space bar, but by the key-operated levers.

The carriage has the usual parts co-operating therewith, as for example, paper feed means, ribbon mechanism, etc. These parts

may be of any suitable construction. As shown, a paper table or apron 99^a is provided with lugs 100, which are held to rock with the shaft 101 which extends lengthwise of the carriage between the carriage frame 70 plates 51. The paper table 99^a extends about the lower portion of the platen 49, and at the forward portion thereof is divided and made to support the ends of the shafts on which three short feed rolls 102 are mounted, these rolls being located at intervals under the front edge of the platen and are normally forced against the platen to engage the work sheet to feed the sheet with the platen when the latter is rotated. Opposite the spaces between the front feed rolls is a pair of rear feed rolls 103. These rolls 103 are mounted on the rear ends of sheet metal supports 104, which have their front portions rigidly connected to the upper surface of the rail 53. The supports for the front feed rolls cross and overlap the edges of the rear roll supports, and by moving the upper edge of the paper table forwardly both front and rear feed rolls are withdrawn from the platen, it being understood that the supports for both front and rear rolls may be of sheet metal, and of spring temper.

Two ribbon spools 105 and 106 are mounted to rotate on extensions 107 projecting inwardly from the side rails 63 of the shift rail 58 and partake of the shifting movement of said frame. The ribbon spools are similarly constructed. Each comprise two sheet metal disks 108 and 109, Fig. 4, having a spacing sleeve 110 and an inner sleeve 111, which passes through the disks and has its ends riveted to hold the several parts together. A short flanged tube 112 is mounted on a fixed stud 113 and a ratchet wheel 114 rests on the flange end of said tube 112, a thin spacing washer being placed on the ratchet wheel to space the spool therefrom. A knurled nut 115 is screwed on to the threaded end of the tube 112 to clamp the ratchet wheel to the spool, the studs 113 being fixed to the brackets 107. Each ratchet wheel is adapted to be engaged by a pawl 116, each of which has its upper end rigidly secured to one of the levers 81 and its lower end shaped to act as a driving pawl on the ratchet wheel under the spool with every movement of the universal bar, and on each of the brackets 107 is a stationary pawl acting to prevent backward movement of the ratchet wheels at all times. The ratchet wheels in operation rotate slowly in opposite directions whenever the machine is in use, and the ratchet wheel of the driving spool must be locked to its spool by means of the nut 115 to cause the spool to rotate with its ratchet wheel, the other spool being loose upon its stud 113. To reverse the feed of the ribbon the winding spool is released from its driving ratchet and the other wheel don-

nected to its spool by tightening the knurled nut 115 of that spool. The brackets 107 are continued inwardly and forwardly from the spool centers and each is provided with an upwardly extending slotted guide 116^a for the ribbon of the usual form, these guides being made of sheet metal and riveted or otherwise held to their supporting brackets.

10 From the guides 116 the ribbon passes rearwardly through a vibrator 117. The vibrator is located in the rear of the center guide 118 for the type-bars. This ribbon vibrator is rigidly secured at its lower end 15 to the transversely extending rod 85, and partakes of the upward movement thereof. The upper end of the vibrator is normally just below a line extending from the printing point to the pivots 82, which causes the 20 ribbon to pass substantially straight up and down in front of the printing point every time the universal bar is depressed. It will be evident that the connection between the levers 81 and the links 80 is in line with the 25 pivots 61 for the shift frame or near enough to that line to cause the ribbon to vibrate substantially the same in the different positions of the shift frame.

The machine may be provided with tabulating means, and may have stops for margin purposes. As shown, there are two adjustable margin stops 119 and 120. These stops each comprise a slotted block and a retaining spring 121, and are adapted to be 30 adjusted to different positions on the slotted parts 122 of the bar 54 of the shift frame. A normally fixed stop 123 is held to the front carriage rail 52 by means of screws 124 or otherwise. This stop comprises a base 35 125 which is pivotally held to a stop or stop member 126. This stop 126 is pivoted at 127 to the bracket or base 125, and has its forward end 128 adapted to engage the margin stops, and with a finger portion 129 by 40 which the stop may be raised to free the same from engagement with either of the margin stops 119 and 120. The stop 123 limits the travel of the carriage, and may be raised clear of either of the stops when it is 45 desired to write outside of the margins, there being a concealed spring acting to hold the front end of the stop 128 normally in line with the margin stops 119 and 120.

As a means to permit the carriage to be 50 adjusted along the support independent of the escapement mechanism, any suitable means may be employed. As one means, the rack 59 is provided with forwardly extending arms 131 and 132, which are pivoted by 55 screws 133 to the end frames of the carriage.

One of the rack arms, as 132, is provided with a forwardly extending handle portion 134, by which the rack may be released from the escapement pinion to adapt the carriage 60 65 to be moved to any desired position at the

will of the operator as is usual in typewriting machines.

While I have shown many features for the purpose of illustrating a machine which is substantially complete in its details and 70 which illustrates the special constructions and mounting of such parts, it will be understood that changes may be made in the specific construction of the typewriter mechanism and in what mechanism or parts are 75 to be mounted on the different frame parts so long as the machine is adapted to be collapsed or made compact; and in this application specific claims to much of the special mechanisms are not included, but such 80 mechanisms have already been covered in separate applications filed by me, or will be covered by separate applications to be filed, many of the claims of this case being confined in a general way to means which adapt 85 a platen shift mechanism to be embodied in a machine which is adapted to be collapsed or be made compact when not in use, whether the frame parts are hinged, as shown, or are otherwise relatively movable.

Having thus described my invention, I claim as new and desire to secure by Letters Patent—

1. In a typewriting machine, the combination of a main frame having parts relatively movable in an up and down direction from a normal operative position to a more compact one when not in use, mechanism mounted on one part of the frame, a type action mounted upon another part of the 95 frame, a carriage, a platen mounted in the carriage, and shift mechanism mounted on a movable part of the main frame for moving the carriage and platen.

2. In a typewriting machine, the combination of a main frame having parts hinged together to adapt one part to have an up and down movement relatively to another, a carriage adapted to travel on the movable frame part, a shift frame for supporting the carriage, and shift mechanism mounted upon the movable frame part and movable with the carriage and main frame part from a normal operative position to a more compact one.

3. In a typewriting machine, the combination of a main frame having parts held together to adapt one part to move relatively to another, a carriage adapted to travel on the movable frame part, a shift frame for supporting the carriage, and shift mechanism mounted upon the movable frame part and movable with the carriage and main frame part from a normal operative position to a more compact one.

4. In a typewriting machine, the combination of a main frame having parts hinged together to adapt one part to have an up and down movement relative to another part, a carriage adapted to travel on the movable 120 125 130 135 140 145 150 155 160 165 170 175 180

frame part, a shift frame for supporting the carriage, and shift-key operated levers mounted upon the movable frame part and movable with the carriage and main frame.

- 5. part from a normal operative position to a more compact one.

5. In a typewriting machine, the combination of supporting means having a plurality of parts relatively movable to adapt the

10 of parts relatively movable to adapt the machine to be made more compact when not in use than when in a normal operative position, type-bars, key-operated levers operatively connected to the type-bars and forming a part of a standard keyboard, a carriage, and shift mechanism forming a part of the keyboard and mounted upon a movable part of the supporting means to partake of the compact movement thereof and during such compact movement moved bodily relatively to the key-operated levers for the type-bars.

15

20

6. In a typewriting machine, the combination of supporting means having a plurality of parts relatively movable to adapt the
25 machine to be made more compact when not in use than when in a normal operative position, types, key-operated levers operatively connected to the types and forming a part of a standard keyboard, and shift mechanism
30 mounted upon a movable part of the supporting means to partake of the compact movement thereof.

7. In a typewriting machine, the combination of a main frame having a plurality of parts relatively movable to adapt the machine to be made more compact when not in use than when in a normal operative position, types, key-operated levers operatively connected to the types, a carriage mounted on a movable part of the frame, and shift mechanism forming a part of the key-board and mounted upon a movable part of the main frame to partake of the compact movement of the carriage and frame part and during such compact movement movable relatively and bodily to the key-operated levers for the types.

8. In a typewriting machine, the combination of supporting means having relatively movable parts, types, a standard keyboard having key-operated levers operatively connected to the types, a platen carriage, and case shift mechanism having keys forming a part of the keyboard and relatively movable with respect to the type-operating keys from a normal operative position to a more compact one.

9. In a typewriting machine, the combination of a main frame having relatively movable parts, types, a standard keyboard having key-operated levers operatively connected to the types, a platen carriage, and case shift mechanism having keys forming a part of the keyboard and mounted on one

of the frame parts and relatively movable with respect to the type-operating keys from a normal operative position to a more compact one. 65

10. In a typewriting machine, the combination of a main frame having a base member, and an outer frame part pivotally held

inner, and an outer frame part pivotally held to the base member at the forward portion thereof to adapt the said outer frame part to have an up and down movement at the

to have an up and down movement at the rear part thereof about the base member substantially to inclose the same when

moved from a normal operative position to a more compact one, types, key-operated levers operatively connected to the types

and mounted upon the base member, a shift frame pivotally held at the forward end thereof to the outer movable frame part, a

connected to the outer movable frame part, a platen carriage movable transversely of the machine, tension mechanism mounted upon the shift frame at the rear thereof, oscillating 85

the shift frame at the rear thereof, escape- 85
ment mechanism also mounted upon the shift frame, ribbon mechanism mounted upon the shift frame, plurality of lift

upon the shift frame, a plurality of shift keys located adjacent to each other and having means to engage a part of the shift frame, the shift frame having a plurality of 90

frame to move the carriage and platen relatively to the types, said shift levers being mounted to partake of the compact movement.

ment of the movable frame part, a universal bar operatively connected to the escapement mechanism and to the ribbon 95

occupying the mechanism and to the ribbon mechanism and mounted upon the movable frame part independent of the shift frame, spacing means, and means whereby the uni-

spacing means, and means whereby the universal bar may be operated by the key-operated levers and the spacing means. 100

11. In a typewriting machine, the combination of a main frame having a base member and an outer frame part pivotally held

to the base member at the forward portion thereof to adapt the said outer frame part to have an up and down movement at the

rear part thereof about the base member substantially to inclose the same when moved from a normal operative position to a more 110

from a normal operative position to a more compact one, types, key-operated levers operatively connected to the types and mounted upon the base member, a shift

mounted upon the base member, a shift frame held to the outer movable frame part, a platen carriage movable transversely 115 of the machine, the shift frame

of the machine on the shift frame, tension mechanism mounted upon the shift frame, escapement mechanism also mounted upon the shift frame.

the shift frame, ribbon mechanism mounted upon the shift frame, a plurality of shift keys located adjacent to each other and hav- 120

is so located adjacent to each other and having means to engage a part of the shift frame to move the carriage and platen relatively to the types, a universal bar oper-

125
tively to the types, a universal bar operatively connected to the escapement mechanism and to the ribbon mechanism and mounted upon the movable frame, part independent of the shift frame, spacing means,

and means whereby the universal bar may be operated by the key-operated levers and the spacing means.

12. In a typewriting machine, the combination of a main frame having a movable frame part movable up and down from a normal operative position to a more compact one, types, key-operated levers operatively connected to the types, a shift frame held to the movable frame part, a platen carriage movable transversely of the machine on the shift frame, tension mechanism mounted upon the shift frame, escapement mechanism also mounted upon the shift frame, ribbon mechanism mounted upon the shift frame, shift means for the shift frame to move the carriage and platen relatively to the types, a universal bar operatively connected to the escapement mechanism and to the ribbon mechanism and mounted upon the movable frame part independent of the shift frame, spacing means, and means whereby the universal bar may be operated by the key-operated levers and the spacing means.

13. In a typewriting machine, the combination of a main frame having a movable frame part movable from a normal operative position to a more compact one, types, key-operated levers operatively connected to the types, a shift frame held to the movable frame part, a platen carriage movable transversely of the machine on the shift frame, tension mechanism mounted upon the shift frame, escapement mechanism also mounted upon the shift frame, ribbon mechanism mounted upon the shift frame, shift means to move the carriage and platen relatively to the types, and a universal bar operatively connected to the escapement mechanism and to the ribbon mechanism and mounted upon the movable frame part and adapted to be operated by the key-operated levers for the types.

14. In a typewriting machine, the combination of a main frame having a movable frame part movable up and down from a normal operative position to a more compact one, types, key-operated levers operatively connected to the types and mounted upon a non-movable member, a shift frame pivotally held to the movable frame part, a platen carriage movable transversely of the machine on the shift frame, tension mechanism mounted upon the shift frame, escapement mechanism also mounted upon the shift frame, ribbon mechanism mounted upon the shift frame, shift means to engage a part of the shift frame to move the carriage and platen relatively to the types, and a universal bar operatively connected to the escapement mechanism and to the ribbon mechanism and mounted upon the movable frame part independent of the shift frame,

spacing means, and means whereby the universal bar may be operated by the key-operated levers and the spacing means.

15. In a typewriting machine, the combination of a main frame base, a main frame part hinged at the forward portion thereof to said base to have an up and down movement thereon so as to be moved from a normal operative position to a more compact one relatively to the base, means for holding the base and frame part in their normal operative position and in their compact position, a carriage, a shift frame for the carriage, and levers located at one side of the machine adjacent to each other, having forwardly extending arms provided with keys and both pivotally held to the movable frame part, said levers having upwardly projecting arms provided with cam slots arranged at an angle with respect to each other and adapted to engage and move the shift frame and when depressed impart an upward movement to said shift frame and carriage by one of said cam slots, and a downward movement by the other cam slot.

16. In a typewriting machine, the combination of a main frame base, a main frame part held to said base to move from a normal operative position to a more compact one relatively to the base, means for holding the base and frame part in their normal operative and compact positions, a carriage, a shift frame for the carriage, and a lever located at one side of the machine having means to move the shift frame, and mounted on the movable frame part.

17. In a typewriting machine, the combination of a main frame base, a main frame part hinged at the forward portion thereof to said base to have an up and down movement thereon so as to be moved from a normal operative position to a more compact one relatively to the base, a carriage, a shift frame, levers located at one side of the machine adjacent to each other, having forwardly extending arms provided with keys and both pivotally held to the movable frame part, said levers having upwardly projecting arms provided with means to engage a part of the shift frame and when depressed imparting an upward movement to said shift frame and carriage by one of said levers, and a downward movement by the other lever.

18. In a typewriting machine, the combination of a main frame having relatively movable parts movable from a normal operative position to a more compact one when not in use, a shift frame, a platen carriage and coöoperating parts mounted upon the shift frame, a universal bar mounted upon the movable frame part independent of the shift frame, key-operated levers adapted to operate the universal bar when

depressed, types operated by the key operated levers, and case shift means for the shift frame.

19. In a typewriting machine, the combination of a main frame having relatively movable parts movable from a normal operative position to a more compact one when not in use, a shift frame, a platen carriage and coöperating parts mounted upon the shift frame, a universal bar mounted upon the movable frame part independent of the shift frame, key-operated levers adapted to operate the universal bar when depressed, types operated by the key-operated levers, and both mounted on a normally fixed part of the frame, and case shift means for the shift frame.

20. In a typewriting machine, the combination of a main frame having relatively movable parts, a type action mounted upon one part, a platen carriage mounted upon another part, and case shift mechanism mounted upon the same part as the platen carriage.

21. In a typewriting machine, a main frame having a part movable to a compact position, and case shift mechanism mounted entirely on said part.

22. In a typewriting machine, the combination of a base frame part, a movable frame part held to the base frame part and adapted to be moved from a normal elevated operative position downwardly into more compact relation to the base frame part, a carriage support mounted on the movable frame part and movable in unison therewith to and from compact position, a platen carriage mounted on said support, and means whereby said carriage support may be moved relatively to the movable frame part to impart a case shift movement to the platen carriage.

23. In a typewriting machine, the combination of a base frame part, a movable frame part held to the base frame part and adapted to be moved from a normal elevated operative position downwardly into more compact relation to the base frame part, a carriage support pivotally held to the movable frame part and movable in unison therewith to and from compact position, a platen carriage mounted on said support, and means for moving said support about its pivot relatively to the movable frame part to impart a case shift movement to the platen carriage.

24. In a typewriting machine, the combination of a main frame comprising a base frame part and a frame part movable from a normal operative position to a more compact position when the machine is not in use, a carriage support mounted on said movable frame part, a platen carriage mounted on said support, said movable frame part and carriage support being mov-

able in unison to and from compact position, connections between said movable frame part and support for permitting the support to be moved relatively to said frame part, and key-operated means for moving said support independently of the movable frame part to impart a case shift movement to the platen carriage.

25. In a typewriting machine, the combination of a main frame comprising a base frame part and a frame part movable from a normal operative position to a more compact position when the machine is not in use, a key action and type bars mounted on the base frame part, a carriage support mounted on said movable frame part, a platen carriage mounted on said support, said movable frame part and carriage support being movable in unison to and from compact position, pivotal connections between said movable frame part and said support for permitting the support to be moved relatively to said frame part, and key-operated means for moving said support independently of the movable frame part to impart a case shift movement to the platen carriage.

26. In a typewriting machine, the combination of a base frame part, a movable frame part held to the base frame part, a carriage support mounted on said movable frame part, a key action and type bars mounted on the base frame part, a platen carriage adapted to travel along said support, said support and movable frame part being movable in unison relatively to the base frame part from a normal operative position to a more compact inoperative position, and means whereby said carriage support may be moved relatively to the base frame part and the movable frame part to impart a case shift movement to the platen carriage.

27. In a typewriting machine, the combination of a base frame part, a movable frame part pivotally held adjacent its forward end to the base frame part, a carriage support pivotally held adjacent its forward end to said movable frame part, a key action and type bars mounted on the base frame part, a platen carriage adapted to travel along said support, said support and movable frame part being movable in unison relatively to the base frame part from a normal operative position to a more compact inoperative position, and means for moving said carriage support upon its pivot relatively to the base frame part and the movable frame part to impart a case shift movement to the platen carriage.

28. In a typewriting machine, the combination of a base frame part, a movable frame part held to the base frame part, a carriage support mounted on said movable frame part, a key action and type bars mounted on the base frame part, a platen

carriage adapted to travel along said support, said support and movable frame part being movable in unison relatively to the base frame part from a normal operative 5 position to a more compact inoperative position, a universal bar mounted to partake of the movement of said support and movable frame part to and from compact position, and means whereby said carriage support 10 may be moved relatively to the base frame part and the movable frame part to impart a case shift movement to the platen carriage.

29. In a typewriting machine, the combination of a base frame part, a movable frame part held to the base frame part, a carriage support mounted on said movable frame part, a key action and type bars mounted on the base frame part, a platen carriage adapted to travel along said support, said support and movable frame part being movable in unison relatively to the base frame part from a normal operative position to a more compact inoperative position, a universal bar mounted to partake of the compacting movement 25 of the movable frame part and carriage support, ribbon and escapement mechanisms mounted to partake of the compacting movement of the movable frame part and carriage support and operatively connected with the universal bar, and means whereby said carriage may be moved relatively to the base frame part and the movable frame part to impart a case shift movement to the platen carriage.

30. In a typewriting machine, the combination of a base frame part, a movable frame part held to the base frame part, a carriage support mounted on said movable frame part, a key action and type bars mounted on the base frame part, a platen carriage adapted to travel along said support, said support and movable frame part being movable in unison relatively to the base frame part from a normal operative 40 position to a more compact inoperative position, a universal bar mounted on the movable frame part independently of the carriage support, ribbon mechanism mounted on the carriage support, escapement mechanism mounted on the carriage support, means maintaining an operative connection between the universal bar and said ribbon and escapement mechanisms in all positions of the movable frame part and carriage support, and means whereby said carriage support may be moved relatively to the base frame part and the movable frame part to 45 impart a case shift movement to the platen carriage.

31. In a typewriting machine, the combination of a base frame part, a keyboard mounted on the base frame part, upwardly and rearwardly movable type bars mounted on the base frame part and operatively connected with the keyboard, a platen carriage

having an opening to permit the movement of the type bars therethrough toward and from the printing point, means for supporting the carriage in substantially overhanging relation with the type bars, said supporting means being movable to impart a case shift movement to the platen carriage, and means whereby said support and carriage may be moved bodily from a normal elevated operative position to a lower inoperative position in substantially overhanging relation to the type bars.

32. In a typewriting machine, the combination of a base frame part, a keyboard, upwardly and rearwardly movable type bars mounted on the base frame part and operatively connected with the keyboard, a platen carriage having an opening to permit the movement of the type bars therethrough toward and from the printing point, means for supporting the carriage in substantially overhanging relation with the type bars, said supporting means being movable to impart a case shift movement to the platen carriage, means whereby said support and carriage may be moved bodily from a normal elevated operative position to a lower inoperative position in substantially overhanging relation to the type bars to make the machine more compact when not in use, escapement mechanism and ribbon mechanism mounted to partake of the movement of the carriage to and from compact position, and a universal bar operatively connected with the ribbon mechanism and escapement mechanism and mounted to partake of the movement of the carriage to and from compact position.

33. In a typewriting machine, the combination of a base frame part, a keyboard mounted on the base frame part, upwardly and rearwardly movable type bars mounted on the base frame part and operatively connected with the keyboard, a platen carriage having an opening to permit the movement of the type bars therethrough toward and from the printing point, means for supporting the carriage in overhanging relation with the type bars, and means whereby said support and carriage may be moved bodily from a normal elevated operative position to a lower inoperative position in overhanging relation to the type bars.

34. In a typewriting machine, the combination of a base frame part, key-operated levers, upwardly and rearwardly movable type bars mounted on the base frame part and operatively connected with the key-operated levers, a platen carriage having an opening to permit the movement of the type bars therethrough toward and from the printing point, means for supporting the carriage in substantially overhanging relation to the type bars, said supporting means being movable to impart a case shift move-

ment to the platen carriage, means whereby said support and carriage may be moved bodily from a normal elevated operative position to a lower inoperative position in substantially overhanging relation to the type bars to make the machine more compact, and a universal bar mounted to partake of the movement of the carriage toward and from compact position, and adapted to be operated by the key-operated levers.

35. In a typewriting machine, the combination of a base frame part, a keyboard mounted on the base frame part, upwardly and rearwardly movable type bars mounted on the base frame part and operatively connected with the keyboard, a movable frame part pivotally held to the base frame part adjacent its forward end, a rearwardly and downwardly inclined platen carriage having an opening to permit the movement of the type bars therethrough toward and from the printing point, a support for the platen carriage, means for pivotally connecting the forward end of the platen carriage support to said movable frame part, key-operated means for moving said support about its pivotal point to impart a case shift movement to the platen carriage, said support and carriage being movable bodily with said movable frame part from a normal elevated operative position to a lower inoperative position to make the machine more compact when not in use.

36. In a typewriting machine, the combination of a base frame part, a keyboard mounted on the base frame part, type bars mounted on the base frame part and operatively connected with the keyboard, a movable frame part, a platen carriage supported at the rear of said movable frame part, means for imparting a case shift movement to said carriage, and connections between said frame parts whereby said carriage may be moved substantially vertically and in an upright position from a normal elevated operative position into a more compact inoperative position when the machine is not in use.

37. In a typewriting machine, the combination of a base frame part, a keyboard mounted on the base frame part, upwardly and rearwardly movable type bars mounted on the base frame part and operatively connected with the keyboard, a platen carriage having an opening to permit the movement of the type bars therethrough toward and from the printing point, a movable frame part pivotally held adjacent its forward end to the base frame part and movable from a normal elevated operative position to a lower inoperative position, a shift frame pivotally held to the movable frame part and adapted to support the platen carriage, key-operated means for moving said shift frame about its pivotal

point to impart a case shift movement to the platen, said shift frame and said movable frame part being movable in unison toward and from compact position.

38. In a typewriting machine, the combination of a base frame part, type bars mounted on the base frame part, key-operated levers mounted on the base frame part and operatively connected with the type bars, a movable frame part, a platen carriage supported on the movable frame part and movable therewith from a normal elevated operative position to a more compact inoperative position, a universal bar adapted to be actuated by the key-operated levers and mounted to partake of the movement of said movable frame part toward and from compact position, escapement mechanism mounted to partake of the movement of the carriage toward and from compact position and operatively connected with the universal bar, a space bar mounted on the base frame part, and a lever mounted on the base frame part and operatively connected with the space bar to actuate said universal bar when the space bar is depressed.

39. In a typewriting machine, the combination of a base frame part, a keyboard mounted on the base frame part, upwardly and rearwardly movable type bars mounted on the base frame part and operatively connected with the keyboard, a platen carriage having an opening to permit the movement of the type bars therethrough toward and from the printing point, case shift mechanism for the platen carriage, a movable frame part forming a foldable support for the platen carriage, and connections between said frame parts to adapt said movable frame part to be shifted downwardly to move the carriage from a normal elevated position overhanging the type bars to a lower inoperative position in substantially overhanging relation to the type bars.

40. In a typewriting machine, the combination of a main frame comprising a base frame part and a movable frame part, pivotally held together adjacent their forward ends, type bars mounted on the base frame part, key-operated levers mounted on the base frame part and operatively connected with the type bars, a platen carriage, a shift frame pivotally held at its forward end to the movable frame part and adapted to support the carriage, a universal bar, a forwardly extending arm pivoted at its rear end to the movable frame part and supporting the universal bar in position to be operated by the key levers, a lever pivotally held to the shift frame, a link connected at its lower end to said forwardly extending arm and pivotally connected at its upper end with the forward end of said lever at a point coincident with the pivotal point of the shift frame, escapement mechanism

mounted on the shift frame, ribbon mechanism mounted on the shift frame, and means operated by said lever for actuating said ribbon and escapement mechanism.

- 5 41. In a typewriting machine, the combination of a main frame, comprising a base frame part and a movable frame part pivotally held together adjacent their forward ends, type bars mounted on the base frame 70
10 part, key-operated levers mounted on the base frame part and operatively connected with the type bars, a platen carriage, a shift frame pivotally held at its forward end to the movable frame part and adapted to support the carriage, ribbon mechanism mounted 75
15 on the shift frame, escapement mechanism mounted on the shift frame, a universal bar mounted on the movable frame part independently of the shift frame, 80
20 means mounted on the shift frame for actuating the ribbon and escapement mechanism, and an operating connection between the universal bar and said actuating mechanism having a hinged connection with said mechanism 85
25 at a point coincident with the pivotal point of the shift frame.

42. In a typewriting machine, the combination of a main frame, type bars mounted on said frame, key-operated levers operatively connected with the type bars, a shift frame pivotally held at its forward end to the main frame, a platen carriage mounted on the shift frame, ribbon and escapement mechanism mounted on the shift frame, a 90
30 universal bar mounted on the main frame, means mounted on the shift frame for actuating the ribbon and escapement mechanism, and an operating connection between the universal bar and said actuating mechanism 95
35 having a hinged connection with said mechanism at a point coincident with the pivotal point of the shift frame, and key-operated means for oscillating the shift frame to impart a case shift movement to the platen 100
40 carriage.

43. In a typewriting machine, the combination of a main frame, type bars mounted on said frame, key-operated levers operatively connected with the type bars, a shift frame pivotally held adjacent its forward end to the main frame, key-operated means for oscillating the shift frame, a platen carriage mounted on the shift frame, ribbon feeding and vibrating means mounted on the shift frame, a lever mounted on the shift frame, means carried by said lever for actuating the ribbon feeding and vibrating means, a universal bar pivotally held to the main frame, and a link connected at one end 105
50 to the universal bar and pivotally connected at its opposite end with said lever at a point coincident with the pivotal point of the shift frame.

44. In a typewriting machine, the combination of a main frame, type bars mounted 110
55

on said frame, key-operated levers operatively connected with the type bars, a shift frame pivotally held adjacent its forward end to the main frame, key-operated means for oscillating the shift frame, a platen carriage mounted on the shift frame, escapement mechanism mounted on the shift frame, a lever mounted on the shift frame, means carried by said lever for actuating the escapement mechanism, a universal bar 75
60 pivotally held to the main frame, and a link connected at one end to the universal bar and pivotally connected at its opposite end with said lever at a point coincident with the pivotal point of the shift frame.

45. In a typewriting machine, the combination of a base frame part, a movable frame part pivotally held adjacent its forward end to the base frame part, means for supporting the rear end of the movable frame part in a normal elevated operative position relatively to the base frame part, said supporting means being adapted to permit the rear end of the movable frame part to have a substantially vertical movement at the rear of 90
65 its pivotal point toward and from a lower position in more compact relation with the base frame part, a platen carriage movable with said movable frame part while upright toward and from compact position, means 95
70 for imparting a case shift movement to the platen carriage, type bars mounted on the base frame part, and key-operated levers for actuating the type bars.

46. In a typewriting machine, the combination of a base frame part, a movable frame part pivotally held adjacent its forward end to the base frame part, means for supporting the rear end of the movable frame part in a normal elevated operative position relatively to the base frame part, said supporting means being adapted to permit the rear end of the movable frame part to have a substantially vertical movement at the rear of 100
75 its pivotal point toward and from a lower 105
80 position in more compact relation with the base frame part, a platen carriage movable with said movable frame part while upright toward and from compact position, means for moving the carriage relatively to said 110
85 movable frame part for imparting a case shift movement to the platen carriage, type bars mounted on the base frame part, and key-operated levers for actuating the type bars.

47. In a typewriting machine, the combination of a base frame part, a movable frame part movable from a normal elevated position to a lower and more compact position with relation to the base frame part, a 115
90 platen carriage movable with said movable frame part from a normal elevated position while upright toward and from a lower and more compact inoperative position, connections between said frame parts for main- 120
95

taining the carriage in an upright position in all positions of the movable frame part, type bars mounted on the base frame part, key-operated levers for actuating the type bars, and means for moving the carriage relatively to said movable frame part to impart a case shift movement to said carriage.

48. In a typewriting machine the combination of a main frame part, a keyboard and type action mounted thereon, a relatively movable frame part, a platen carriage mounted on said movable frame part, connections between said frame parts for maintaining the platen carriage in an upright position when said movable frame part is shifted to move the platen carriage to an inoperative position relatively to the type action to make the machine more compact when not in use, and means for imparting a case shift movement to the platen carriage.

49. In a typewriting machine, keys forming a part of a standard keyboard, a type bar for each key, a platen carriage, ribbon mechanism movable downwardly with the platen carriage while upright to an abnormal position to make the machine compact and to reduce its height, and means including keys forming a part of the keyboard for shifting the platen carriage. 30

50. In a typewriting machine, a main frame having one part vertically movable on another part and movable to an abnormal compact position while upright, a platen carriage mounted on the vertically movable frame part, and case shift means for the platen carriage for moving the latter independent of the compact movement. 35

This specification signed this 28th day of June, A. D. 1916.

EMMIT G. LATTA.
